UNITED STATES PATENT OFFICE.

CARLETON H. HUTCHINSON, OF HANOVER, MASSACHUSETTS.

INTERNAL-COMBUSTION ENGINE.

Application filed February 2, 1920. Serial No. 255,655.

To all whom it may concern:

Be it known that I, CARLETON H. HUTCHINSON, a citizen of the United States, residing at Hanover, county of Plymouth, 5 State of Massachusetts, have invented a certain new and useful Improvement in Internal-Combustion Engines, of which the following is a specification, reference being had therein to the accompanying drawings.

10 The invention relates to a new and useful improvement in internal combustion engines, having two pistons within each cylinder, namely a piston proper and a sub-piston. The invention is an improvement 15 on the invention shown and described in an application filed by me December 1, 1919, Serial No. 341,713. The sub-piston of the engine shown and described in said prior application is actuated by means of a cam 20 mounted on a crank shaft and engaging with the roll on the lower end of the stem of the sub-piston. The present invention relates to the sub-piston stem.

The invention will be fully understood 25 from the following description when taken in connection with the accompanying drawings, and the novel features thereof will be pointed out and clearly defined in the claims at the close of this specification.

30 In the drawings, Fig. 1 is a vertical cross section of a two-cycle internal combustion engine embodying the invention, showing the piston and sub-piston both at the top dead center in the position at the end of 35 the compression stroke with the exhaust valve closed ready for the ignition.

Fig. 2 is a view showing the cam and the sub-piston stem in the position that they will occupy when within 45° of the bottom dead center after both pistons have been driven down by the explosion and just before the main piston has descended far enough to open the intake port and just before the sub-piston begins to rise for the 45 suction and scavenging movement and just after the exhaust valve has been opened. For the purpose of the present invention, however, it is deemed necessary to show in this view only the sub-piston stem and the 50 cam.

Fig. 3 is a view of the sub-piston stem, the upper end of the stem being broken away.

Referring now to the drawings, 1 represents the cylinder and 2 the frame on which the cylinder is supported, and 3 the crank

shaft journalled in bearings carried by the frame. The cylinder 1 is provided with an intake port 5 and an exhaust port 6 controlled by an exhaust valve 15. Within the 60 cylinder are the main piston 7 and the sub-piston 8. The main piston 7 is connected by a split connecting rod 9 with the crank pin 11 of the crank arm 10.

The sub-piston 8 is mounted on the upper 65 end of a stem 12 whose lower end is bent at right angles to the depending main portion 12 of the stem forming an arm 12, thus giving to the stem an L-shaped appearance. The cam rotates counter-clockwise, 70 that is towards the left as viewed in Figure 1, and the arm 12 extends toward the right, that is in the opposite direction to the direction of rotation of the cam. Within the lower side of the arm 12 of the 75 sub-piston stem are a series of rolls or ball-bearings 13, which are adapted to engage with the periphery of the cam. The left-hand one of these rolls or ball-bearings 13 is directly in line with the axis of 80 the vertical portion of the stem 12. When the parts are in the position shown in Figure 1 at the upper dead center, only the left-hand ball 13, that is the one at the heel of the sub-piston stem is in engagement 85 with the cam, and this will be true during the time that the convex portion of the cam periphery is in engagement with the sub-piston stem. When, however, the cam revolves into the position shown in Figure 90 2 so that the sub-piston stem is in engagement with the drop or reentrant portion, or incurve of the cam, the other balls on the arm 12 of the sub-piston stem will gradually be brought into engagement with 95 the cam so that when the cam turns into the position shown in Figure 2 within 45° of the bottom dead center and the substantially straight portion *a* of the cam 14 is in horizontal position, all of the balls 13 will 100 simultaneously engage the periphery of the cam.

In the form of sub-piston stem shown in the said prior application, Serial No. 341,713, the sub-piston stem was straight, consisting only of the vertical portion of the sub-piston stem shown in the present application, and when the cam was turning from the 45° position shown in Figure 2 of the present application where the left-hand 110 ball-bearing engages the cam at the point *b* to the position where the point *c* at the

other end of the said horizontal portion a in the periphery of the cam comes into engagement with the sub-piston stem, the cam had to exert in the engine shown in 5 said former application what I would term an upward push upon the sub-piston stem. By the use of the bent arm 12^a as shown in the present application it will be seen that while the cam is in the position shown in 10 Figure 2, a considerable extent of the cam surface is at one time in engagement with the whole length of the arm 12^a or with the several ball-bearings distributed through the length of the arm 12^a . As the 15 cam continues to turn from the position shown in Figure 2 where the horizontal portion of the cam is in engagement with all of the balls, the cam will at first be in engagement with the right-hand ball only, 20 the remaining balls being lifted out of engagement with the surface of the cam, then it will engage with the second ball from the right-hand end, and so on, passing from one to the other, engaging with one or two 25 balls simultaneously until the high point of the cam is reached when it will then engage the left-hand ball only.

What I claim is:—

1. An internal combustion engine, having 30 a cylinder, a main piston and a sub-piston movable in said cylinder, a crank shaft, a cam mounted on said crank shaft and rotating therewith, a stem connected with the

sub-piston whose lower end engages with said cam, said lower end having an arm 35 bent at a right angle to the main portion of the stem, said cam being formed with a reentrant portion which at certain points in the rotation of the cam engages with the said arm for substantially the full 40 length of said arm where it rides over a flat portion of the cam, and as it rides over the convex surface of the cam, the contacting portion gradually recedes to the heel 45 of the arm.

2. An internal combustion engine, having a cylinder, a main piston and a sub-piston movable in said cylinder, a crank shaft, a cam mounted on said crank shaft and rotating therewith, a stem connected with 50 the sub-piston whose lower end engages with said cam, said lower end having an arm bent at a right angle to the main portion of the stem, said arm being provided with a series of ball-bearings which engage 55 with the reentrant portion of the cam at certain periods in the rotation of the cam for substantially the full length of said arm where it rides over a flat portion of the cam, and as it rides over the convex surface of the 60 cam, the contacting portion gradually recedes to the heel of the arm.

In testimony whereof I affix my signature.

CARLETON H. HUTCHINSON.
